Primary Examiner — Mark Goodwin*(74) Attorney, Agent, or Firm* — Wenderoth, Lind & Ponack, L.L.P.(57) **CLAIM**

The ornamental design for a thrust roller bearing, as shown and described.

DESCRIPTION

FIG. 1 is a top view of the thrust roller bearing showing our new design;

FIG. 2 is a bottom view thereof;

FIG. 3 is a front view thereof;

FIG. 4 is a rear view thereof;

FIG. 5 is a right side view thereof;

FIG. 6 is a left side view thereof;

FIG. 7 is a perspective view thereof; and,

FIG. 8 is a sectional view thereof taken along line 8-8 in FIG. 1.

The broken line showing of the inner race is included for the purpose of illustrating portions of the thrust roller bearing and forms no part of the claimed design.

1 Claim, 8 Drawing Sheets(56)
